UNITED STATES PATENT OFFICE

MICHAEL J. STARK, OF BUFFALO, NEW YORK, ASSIGNOR TO GEORGE J. RECORD, OF CONNEAUT, OHIO.

SAP-SPOUT.

SPECIFICATION forming part of Letters Patent No. 269,545, dated December 26, 1882.

Application filed October 16, 1882. (No model.)

To all whom it may concern:

Be it known that I, MICHAEL J. STARK, of Buffalo, in the county of Erie and State of New York, have invented certain new and useful 5 improvements on Sap-Spouts; and I do hereby declare that the following description of my said invention, taken in connection with the accompanying sheet of drawings, forms a full, clear, and exact specification, which will enable others skilled in the art to which it ap- 10 pertains to make and use the same.

My present invention has general reference to sap-spouts; and it consists essentially in the novel and peculiar combination of parts 15 and details of construction, as hereinafter first fully set forth and described, and then pointed out in the claims.

In the drawings already mentioned, which serve to illustrate my said invention more fully, 20 Figure 1 is a perspective view of my improved sap-spool. Fig. 2 is a plan of the same. Fig. 3 is a sectional view in line x x of Fig. 2, looking toward the small end of the spout. Fig. 4 is a perspective view of the locking-shield 25 detached, drawn on a magnified scale. Fig. 5 is a plan of the band and stay blank. Figs. 6 and 7 are views of a modified form of my said invention.

Like parts are designated by corresponding 30 letters of reference in all the figures.

The object of my present invention is the production of a simple, cheap, and durable sap-spout, capable of being produced entirely from sheet metal with but little hand-labor. To attain this end I construct my sap-spout from a 35 tapering tube, A, of one or more thicknesses of metal, butted at their joints or lapped, as preferred. Upon this tapering tube I slide a combined band and stay, B C, said band B 40 being composed of a perfectly plain strip of metal, the ends of which, b b' , converge from a point opposite to that from which the curvature of said strip B is obtained.

This strip B, I form into the shape shown in 45 Fig. 3, after which I place over the two meeting ends b b' a shield, D, consisting of a flat strip of metal having centrally a slotted aperture, d . This shield serves the double purpose of first locking the band by means of its slot-hole d , 50 while the portions d' d'' , covering part of the

longitudinal seam of the taper tube, act as a reinforce for said tube, while the part D'' also serves as an intermediary between the bail of a sap-pail and the spout to prevent said bail from rubbing upon the tube A, thus adding 55 greatly to the durability of the said sap-spout.

In the drawings I have shown the tube A as composed of two similar parts, one within the other, with the joints at different places. Although this construction is the most satisfactory one for practical purposes, I do not wish to confine myself to such construction. In fact, a single tube with the joint either butting or lapped, when made of proper material, will be found practically sufficient for all purposes, 60 especially so in view of the fact that the re-enforcing and locking shield adds strength to the tube. Nor need I confine myself strictly to the construction of the band B as shown in Fig. 5, since I can form the said band and the 65 said shield in one piece of metal, as illustrated in Fig. 7. In this latter figure the parts b b' b'' correspond with the parts b b' of Fig. 5, while the part D, with its projections d' and d'' and slot-hole d , corresponds with the shield shown 70 in Fig. 4. This construction of the combined band, stay, and shield in one piece has decided advantages, first of which is that in manufacturing sap-spouts I have one piece less to take care of, and that a very small one, too, awkward to handle, and otherwise not very desirable; but it has the disadvantage that the band is not so readily formed and the stay portion passed through the slot-hole d , so that, taking 75 all things into consideration, one of the bands will be about as readily manufactured as the other.

I am well aware that sap-spouts have been made in which the tube is constructed of two similar pieces placed one into the other, and 80 in which a combined band and stay has been used that was constructed of a single piece of metal. In acknowledging the state of the art I have special reference to several patents of Geo. J. Record, particularly the one of September 26, 1882, No. 265,146, in which a combined band and stay is shown constructed of a single piece of metal. This construction of the band, as shown, cannot, however, be practically carried out. The punching of the notches, 85

the bending of the part beyond the notches, so as to pass it through the opening shown, then the straightening out again of said part, and the folding over are all operations which 5 cannot be practically carried into effect without making the article cost much more than it can bring in the open market, while the notches and perforations in the band weaken the same to such an extent as to render the same perfectly useless.

It will thus be readily seen that in the construction of my sap-spout I have overcome all the objections to the spout mentioned and produced an article much superior and far more 15 desirable than that.

Having thus fully described my invention, I claim as new and desire to secure to me by Letters Patent of the United States—

1. In sap-spouts, a combined band, stay, and 20 re-enforcing shield, substantially as and for the object stated.

2. In sap-spouts, a band, substantially as described, in combination with a locking and re-enforcing shield, as and for the purpose indicated.

3. The hereinbefore-mentioned combined band, stay, and re-enforcing locking-shield, consisting of a single piece of metal, having the main curved portion B b, converging portion b' b'', and the shield D, with slotted aperture 30 d, the whole being constructed and adapted for application to a tube, A, substantially as and for the purpose specified.

In testimony that I claim the foregoing as my invention I have hereto set my hand in the 35 presence of two subscribing witnesses.

MICHAEL J. STARK.
